UNITED STATES PATENT OFFICE.

SARAH VAN DUZER, OF NEW YORK, N. Y.

NAPKIN-HOLDER.

SPECIFICATION forming part of Letters Patent No. 793,478, dated June 27, 1905.

Application filed November 4, 1904. Serial No. 231,461.

To all whom it may concern:

Be it known that I, SARAH VAN DUZER, a citizen of the United States, residing at New York, in the county of New York and State of New York, have invented new and useful Improvements in Napkin-Holders, of which the following is a specification.

This invention relates to napkin-holders; and the object thereof is to provide a device which embodies the function of a napkin-ring as well as forming a hanger or support for the napkin. To this end the device is adapted for use for holding a napkin in place upon a table and is also adapted as a convenient and efficient means for attaching the napkin to the wearing-apparel of a person using the napkin, so that the napkin will act as a covering and protection for the dress while eating.

The invention further aims to provide a napkin-holder which shall be simple in its construction, strong, durable, efficient in its use, and comparatively inexpensive to manufacture.

In describing the invention in detail reference is had to the accompanying drawings, which form a part of this invention and wherein is shown the preferred embodiment of the invention; but it is evident that changes, variations, and modifications can be made which come within the scope of the claim hereunto appended.

In the drawings, wherein like reference characters denote corresponding parts throughout the several views, Figure 1 is a perspective view showing a napkin-holder constructed in accordance with this invention used as a napkin-ring. Fig. 2 is an elevation illustrating a holder constructed in accordance with this invention used as a support or hanger for connecting the napkin to the wearing-apparel of a person, so as to protect the garment of the person using the napkin while eating; and Fig. 3 is a perspective view of a napkin-holder constructed in accordance with this invention.

A napkin-holder constructed in accordance with this invention is formed from a single piece of spring-wire looped to form a body portion or spring-coil 1, the body portion or spring-coil being formed of two or more loops, preferably in the manner as shown. The curvature of

each of the loops of the body portion 1 extends in the same plane throughout—that is to say, the curve thereof is not broken or mutilated, but continuous in the same plane. One end of the wire is provided with a spherical portion 2, and the said end, which carries the spherical portion 2, is bent rearwardly at a slight inclination, as at 3, to enable the napkin to be readily inserted when it is desired to spread the napkin when connecting it through the medium of the holder to the garment of a person, as shown in Fig. 2. The other end of the wire is bent in a vertical manner, as at 4, and then rearwardly and downwardly at an inclination, as at 5. This manner of bending 65 the wire forms a hook or attaching means for connecting the holder to the garment of a person.

When using the holder as a napkin-ring, the napkin is folded and inserted through the spring-coil, as shown in Fig. 1, and when connecting the napkin to a garment, so as to protect the latter while eating, the napkin is inserted between the coils and spread out in the manner as shown in Fig. 2, and the hooked portion of the holder is inserted over the neck-band of a garment or any other part thereof where the hook can be attached.

Having thus fully described my invention, what I claim as new, and desire to secure by Letters Patent, is—

A napkin-holder comprising a body portion embodying a spring-coil, each of the loops of the coil having the curvature thereof continuous in the same plane, said body portion having one end thereof extending rearwardly at an inclination and the other end vertically, rearwardly and downwardly at an inclination, said rearwardly-extending portions arranged at the back of the body portion, one of said rearwardly-extending portions provided with an enlargement.

In testimony whereof I have hereunto set my hand in presence of two subscribing witnesses.

SARAH VAN DUZER.
